H. H. WALLER.
FIBER TREATING MACHINE.
APPLICATION FILED FEB. 6, 1920.

1,407,364.

Patented Feb. 21, 1922.

Inventor:
Henry H. Waller
By his Attorney: Herbert W. Turner.

UNITED STATES PATENT OFFICE.

HENRY HIRST WALLER, OF HARROGATE, ENGLAND.

FIBER-TREATING MACHINE.

1,407,364.

Specification of Letters Patent. Patented Feb. 21, 1922.

Application filed February 6, 1920. Serial No. 356,781.

(GRANTED UNDER THE PROVISIONS OF THE ACT OF MARCH 3, 1921, 41 STAT. L., 1313.)

To all whom it may concern:

Be it known that I, HENRY HIRST WALLER, a subject of the King of Great Britain, residing at Harrogate, in the county of York, England have invented certain new and useful Improvements in Fiber-Treating Machines, (for which I have filed an application in Great Britain, April 3, 1917, Patent No. 112,078,) of which the following

10 is a specification.

This invention relates to machines for opening all kinds of thread work, cotton, woollen, worsted, rags and the like, of the type in which a toothed cylinder or swift 15 revolving in a casing receives from feed rollers the material, which then passes partly around the cylinder, between the cylinder and the casing, this operation being usually repeated in a set of several successive scutchers or opening machines in series.

According to my invention I secure to the inner surface of the casing under the cylinder a metal segment having six or other 20 number of ribs, between which ribs I secure to the segment toothed lags, the teeth on which are just cleared by the teeth of the rotating cylinder. The cotton or the like in travelling through the machine is thus exposed to the combined action of the

25 stationary teeth on the segment and the revolving teeth of the cylinder, and the lower layer of the travelling cotton not being shielded from teeth by the upper layer as before, the opening effect is so much in-

30 creased that the operation can be performed as well by a series of a less number of cylinders or swifts as it has previously been by a greater number. A great economy in plant, floor space, and motive power is thus effected. Further the finished material is

35 of much more value owing to the preservation of the staple and the avoidance of neps and knots. A trough or tray is fixed slightly beyond the vertical plane of the

40 centre of the cylinder, and the further edge of the said trough, or the flange of the machine casing in which the said trough slides is slightly higher and at a slightly less radial distance from the centre of the cylin-

der than the edge of the rib on the above 50 named segment which is next to the trough, this arrangement allowing the most effective action of the trough.

Such being the nature of the said invention, in order that the same may be clearly 55 understood I have hereto annexed a diagram illustrating the arrangement of the parts mentioned.

The reference numeral 1 indicates a portion of the large swift, 2 the feed rollers, 60 3 the usual knife below the feed rollers, the upper wearing face of which knife I preferably form on a renewable edge piece or bead 4. A metal segment 5 having ribs 6 is secured by brackets 7 to the under-casing 65 of the machine (not shown) and between these ribs 6 are secured lags 8 provided with teeth opposing the teeth on the swift. By this arrangement the toothed lags are prevented from working loose in such manner 70 as to interfere with the proper action of the machine.

The sliding trough or drawer tooth trap 9, which can be drawn out at the side of the machine from its guides 10, has its 75 further side 11 arranged as shown to form a "cliff" against which are thrown loose teeth, broken pieces of lags, pins, screws and other hard materials, which then fall back into the trough.

80 I claim:—

1. In an opening machine, a revoluble toothed cylinder, feed mechanism for supplying material to be treated, a stationary segment arranged below the feed mechanism 85 and provided with ribs, and toothed lags arranged between the said ribs and co-acting with the said cylinder to treat the material fed between them and the cylinder.

2. The combination, with an opening machine constructed as set forth in claim 1, of a removable receptacle for catching hard rubbish discharged with the treated material, said receptacle being arranged at the lower end of the said segment under the 95 said cylinder.

In testimony whereof I affix my signature.

HENRY HIRST WALLER.
